UNITED STATES PATENT OFFICE.

JOSEPH H. WOOLASTON AND THOMAS B. PRIDDY, OF NEW HAVEN, CONNECTICUT, ASSIGNORS TO THE BARNES MANUFACTURING COMPANY, OF SAME PLACE.

LOCK-ESCUTCHEON.

SPECIFICATION forming part of Letters Patent No. 243,029, dated June 14, 1881.

Application filed November 8, 1880. (Model.)

To all whom it may concern:

Be it known that we, JOS. H. WOOLASTON and THOMAS B. PRIDDY, of New Haven, in the county of New Haven and State of Connecticut, have invented new Lock and Latch Escutcheon; and we do hereby declare the following, when taken in connection with the accompanying drawings, and the letters of reference marked thereon, to be a full, clear, and exact description of the same, and which said drawings constitute part of this specification, and represent, in—

Figure 1, a view from the inner or under side; Fig. 2, a transverse central section enlarged; 15 Fig. 3, an outside view.

This invention relates to an improvement in escutcheons for that class of locks which use a flat key, and in which it is necessary for that part of the escutcheon called the "key-guide," 20 through which is the key-hole, to revolve or rotate with the key.

In the usual construction of this class of escutcheons the plate is made flat, and the rotating guide projects beyond the inner surface or plane of the plate. In the case of a thin door, or one in which the end of the tube of the lock will come flush with or near the surface of the door, such guides or escutcheons cannot be used, because the guide will 25 strike the tube before the plate will set upon the surface of the door.

The object of this invention is to overcome this difficulty, and produce a simple and cheap construction of this class of escutcheon; and 30 it consists in the construction hereinafter described, and particularly recited in the claim.

A represents the escutcheon-plate, through which is a central circular opening, B. This opening is made with an inwardly-projecting 35 flange, a, at the outside, and so as to have a shoulder on the inside. On this shoulder the key-guide C is placed so as to lie against the flange, and in the side of the opening in the escutcheon-plate an annular groove, d, is cut 40 close in rear of the key-guide C. Then into this annular groove a divided ring, e, is introduced 45

or sprung, its external diameter when in place corresponding to the extreme diameter of the groove d in the escutcheon-plate, and the internal diameter less than the exterior diameter of the key-guide C, as seen in Fig. 2, so that a bearing is formed for the key-guide in the escutcheon-plate between the flange a and the ring e, the ring serving to hold the key-guide in place and yet permit it to be rotated 50 with the key introduced through the key-hole f therein. The plate A is raised at the center, so as to bring the shoulder on which the key-guide rests so far from the plane of the rear or bearing surface of the plate that the 55 whole length of the key-guide will come forward or outside of the plane of the bearing-surface of the plate, as seen in Fig. 2, so that the tube of the lock may come flush with the surface of the door without interfering with 60 the guide.

It will be understood from the foregoing that we do not broadly claim an escutcheon-plate having a key-guide arranged therein so as to be rotated by the key; neither do we 65 broadly claim securing two parts of a thing together by means of a divided ring resting in an internal annular groove in one part, and so as to bear upon the other part, as such, we are aware, is not new; but

What we do claim is—

The escutcheon-plate A, constructed with the flange a around its central opening and so as to form a shoulder upon its rear side, and the annular groove d in rear of said shoulder, combined with a key-guide, C, constructed to rest upon the said shoulder, and the divided ring introduced into said groove d, in rear of and so as to bear upon the key-guide, to hold the key-guide in place and yet permit 80 its rotation, substantially as described.

J. H. WOOLASTON.
THOMAS B. PRIDDY.
